FRANK C. ANDERSON, OF CINCINNATI, OHIO, ASSIGNOR TO THE AMERICAN VALVE & METER COMPANY, OF CINCINNATI, OHIO, A CORPORATION OF OHIO.

SWITCH-STAND SEMAPHORE MECHANISM.

1,141,906.

Specification of Letters Patent.

Patented June 1, 1915.

Application filed November 20, 1913. Serial No. 802,021.

To all whom it may concern:

Be it known that I, FRANK C. ANDERSON, a citizen of the United States, and a resident of Cincinnati, in the county of Hamilton 5 and State of Ohio, have invented certain new and useful Improvements in Switch-Stand Semaphore Mechanisms, of which the following is a specification.

My invention relates to semaphore mechanism for switch stands of the skeleton or rotary type, and has for its object the complete change of the semaphore arm to "danger" position before opening of the switch can be commenced; and also to lock the semaphore mechanism so that it cannot be brought back to "safety" position until the switch has been completely thrown back to its safe position.

My invention consists in the parts and in 20 the details of construction and arrangement of parts as will hereinafter be more fully described and claimed.

In the drawings: Figure 1 is a general perspective view of a switch stand and 25 semaphore embodying my invention, the parts being in "safe" position; Fig. 2 is a detail side elevation of part of the mechanism showing the switch-operating lever, the semaphore-operating lever in engagement therewith and part of the semaphore connection pivoted to the semaphore-operating lever; Fig. 3 is a vertical cross section on a line corresponding to the line $y-y$ of Fig. 4, showing the construction of the 30 semaphore mechanism; Fig. 4 is a vertical cross section elevation, the section being on a line corresponding to the line $x-x$ of Fig. 3, showing another view of the semaphore mechanism; Fig. 5 is a vertical cross section on a line corresponding to the line $z-z$ of Fig. 1, through the switch stand and 35 semaphore-operating mechanism looking toward the switch-operating lever; Fig. 6 is a detail perspective view of the upper bracket; and Fig. 7 is a similar view of a 40 modification of the lower bracket in which the link is reversible on the bracket.

The switch stand 1 has the main shaft 2 journaled vertically in it, being held in upper and lower bearings by caps 3 and 4, respectively. Below this lower bearing this shaft has the crank 5 to which is pivoted the connecting rod 6 adapted to be connected to the point rails of the switch, not shown 45 herein.

Above the upper bearing, the main shaft 2 has, fixed on it, the fulcrum-head 7, said main shaft being supported by this fulcrum-head 7 bearing down against the upper side of the upper bearing. The top of this switch stand 1 comprises the horizontal plate 10 which has slots 11 and 12 diametrically opposite on a line through the center of the main shaft 2; and the handle or lever 8 is adapted to engage in either one of these slots when the switch is completely thrown one way or the other. The handle or lever 8 has the ear 13 above its pivot 9, with an opening 14 to receive the bow or shackle of a padlock to engage against the outer face 70 of the fulcrum-head 7, whereby the lever 8 may be locked against removal from the slot 11 or slot 12 as the case may be.

It will be seen that the main shaft 2 is thus rotated 180° to throw the switch; and 75 the mechanism so far described is similar to previously disclosed apparatus in switch stands.

The semaphore column 15 is supported rigidly in upper and lower brackets 16 and 17, respectively, which are bolted to the switch stand along with the caps 3 and 4, respectively, of the upper and lower bearings of the shaft 2. This column 15 is preferably hollow, being conveniently made of 80 iron pipe which has its lower end slipped into the lower bracket 17, and fits tightly in an opening in the upper bracket, where it has a bolt 18 passed through it and the brackets, which reinforces the connection 85 between the column and bracket and prevents the column from turning.

The upper end of the semaphore column carries a fulcrum-block 19 screwed onto it, in which is pivoted the semaphore-head 20 95 on a transverse pin 21 passing through bifurcations 22 of the fulcrum-block and through a lug 23 of the semaphore-head 20 which lug is between the bifurcations. This semaphore-head 20 carries the semaphore-arm or blade 24 rigidly attached to it between the longitudinal side flanges 25, so that the arm and the head swing in a vertical plane. The arm extends toward the track and the head 20 has another lug 26 at 100 the side of the fulcrum-block 19 away from the track. The semaphore-operating rod 27 has an upper connecting head 28 with bifurcations 29 which receive the lug 26 between them, and a bolt 30 passes through the 110

bifurcations and the lug, thereby pivoting the rod 27 to the head 20. A lock nut 31 makes the connecting head 28 rigid on the rod 27. This rod 27 extends down through an opening 32 in the upper bracket 16, and, a short distance below this bracket, has a lower connecting head 33, with bifurcations 34, and made rigid on the rod 27 by a lock nut 35.

- 10 To operate the semaphore, a semaphore-operating lever 36 has a pivot 37 in one of the two stops 38 and 39, which are provided on the plate 10 for the fulcrum-head 7. This pivot 37 is concentric with the pivot 9 of the switch-operating lever or handle 8. Projecting from the side of the semaphore-operating lever 36 toward the switch-operating lever 8 is a boss 40 that carries a lug 41, and the switch-operating lever 8 has a slot 42 that receives the lug 41, whereby the semaphore-operating lever 36 is moved along with the switch-operating lever 8, the two levers swinging together on their concentric pivots 9 and 37.
- 15 The lower bracket 17 has a bifurcated fulcrum-lug 43, receiving, between its bifurcations, one end of a link 44 which fulcrums in the lug on a transverse bolt 45. The other end of the link 44 has the lower end of 20 the primary connecting rod 46 at one side, and the lower end of the secondary connecting rod 47 at its other side, both pivoted thereto by a transverse bolt 48 passing through the rods and link. The upper end 25 of the secondary rod 47 is received between the bifurcations 34 of the lower connecting head 33 on the semaphore-operating rod 27, and is pivoted thereto by a transverse bolt 49 passing through the bifurcations and 30 through the rod. The upper end of the primary rod 46 has a reduced threaded part 50 which is screwed into a connecting head 51 and held rigid therein by a lock nut 52. This connecting head 51 receives the 35 stud 53 which is provided near the lower end of the semaphore-operating lever 36 opposite to the boss 40 and lug 41 thereon. The semaphore-operating rod 27 and the other connections are so proportioned that 40 when the switch-operating lever 8 is down in its vertical position and the semaphore-operating lever is in a corresponding position, the semaphore-head and arm will be in such position that the arm slants upwardly out toward the track, thus signaling "safety," but when the switch-operating lever 8 is raised to horizontal position, out of the slot in the plate 10, carrying the semaphore-operating lever 36 to a corresponding 45 position, the semaphore-head and arm will be tilted so that the arm is in substantially horizontal position, thus signaling "danger." It will be seen that the link 44, combined with the primary and secondary connecting rods, causes these rods to trans-

mit the motion of the semaphore-operating lever to the semaphore-operating rod and thence to the semaphore-head and arm.

The threaded connection of the semaphore-operating rod 27 to its upper and lower heads 28 and 33 allows of adjustment of the length of this connecting element thus made up; and the threaded connection of the primary connecting rod 46 to its head 51 allows adjustment of the length of this connecting 75 element.

The fulcrum-block 19 has a lateral extension 54 in which is journaled a vertical lamp shaft 55 with a lamp segment 56 fixed on it and meshing with a segment 57 on the 80 semaphore-head 20, this segment 57 preferably being integral with the head. The upper end of the lamp shaft 55 has a stud 58 so shaped as to be suitable to receive a signal lamp to turn with it. A hood 59 is bolted to the extension 54 of the fulcrum-block and surrounds the lamp shaft 55 and the segments 56 and 57, the top of this hood forming an upper bearing 60 for the lamp shaft 55. This hood protects the mechanism from the weather; and to protect the pivotal connection of the semaphore-head 20 with the fulcrum-block 19, the head is provided with lateral arc-shaped flanges 61 on its sides, extending out over the bifurcations 95 22 of the fulcrum-block 19, to shed the water and prevent its entrance between the lug 23 and these bifurcations 22.

Preferably, the semaphore is designed so that the arm in its upward tilted position is 100 at an angle of 45° with its lowered horizontal position, so that the semaphore head and arm thus have an angular movement of 45°, the various parts being proportioned accordingly, so as to obtain this degree of 105 movement from the movement of the switch-operating lever 8 and semaphore-operating lever 36 through an angle of 90°. The lamp should be rotated through an angle of 90°, and, therefore, the segment 57 of the 110 semaphore-head 20 is made of twice the pitch diameter of the lamp segment 56.

When the switch is to be thrown, the first action of the operator, after removing the padlock from the ear 13, is to bring the 115 lever 8 to a horizontal position, swinging on its pivot 9, and with its upper end, carrying the ear 13, moving down into the interior of the fulcrum-head 7. When this lever has reached this horizontal position it 120 is completely out of the slot 11 or 12, as the case may be. This lever 8, together with the fulcrum-head, now make up the operating lever of the switch stand; and they are swung around over the plate 10 through 125 the required 180°, whereupon the handle or lever 8 is dropped into the slot 12 or 11 at the other side, as the case may be.

As shown in the drawings, the switch stand is so designed that when the lever 8 130

is in the slot 11 it will have closed the switch and a "safe" or "clear" signal will be required of the semaphore. Now, as the lever 8 is raised out of the slot 11, it will 5 raise the semaphore-operating lever 36 with it as before described, which will result in swinging the semaphore-head and arm down through the 45° required to effect the change of signal from "safe" or "clear" to "danger". This completion of the change of 10 signal will occur just as the lever 8 reaches its horizontal position out of engagement with the sides of the slot 11. Then the switch may be thrown, the lever 8 being 15 brought around to the other side of the stand and dropped into the slot 12 thereof.

While the mechanism so far described insures that the semaphore will be operated from "safe" to "danger" position before 20 throwing of the switch is commenced, it will not, in itself, prevent throwing of the semaphore back to "safe" position before the switch itself is thrown back to such position. It will be seen that it would be possible to 25 operate the semaphore by means of the semaphore-operating lever 36 itself after the switch-operating lever 8 had been disengaged therefrom. To prevent this operation of the semaphore mechanism independently 30 of the switch-operating mechanism, I provide a segment 62 on the fulcrum-head 7, concentric with the shaft 2. This segment is so positioned that when the fulcrum-head is in position to permit the lever 8 to occupy 35 the slot 11, the segment will have a terminal part 63 a short distance away from the semaphore-operating rod 27 just above the upper bracket 16; but when the operator commences to swing the fulcrum-head 40 7 around in the horizontal plane, this part 63 will approach the rod 27. To properly engage with the upper side of the segment 62, a keeper 64 is secured on the semaphore-operating rod 27. Preferably, the 45 rod 27 is separated to receive this keeper 64, the lower end of the upper main section being screwed down into the top of the keeper, and the shorter lower section 65 being screwed up into the bottom of the keeper, 50 and these sections being fixed by means of lock nuts 66 bearing against the upper and lower sides of the keeper. This arrangement avoids the necessity of threading the rod from its lower end up to the region 55 where the keeper is to be, but at the same time the keeper may be adjusted up or down on the rod sections to a sufficient degree for this purpose. This keeper 64 has a flange 60 67 extending out from the rod 27 far enough so that it may engage with the segment 62 if the fulcrum-head 7 has been swung around as above described. This keeper 64 is adjusted to such a position on the rod 27 that 65 it will stand very slightly above the level of the upper side of the segment 62 when

the semaphore has been thrown to "danger" position; and the terminal part 63 of the segment 62 being so close to the rod 27 and the flange 67 of this keeper, it will be seen that as soon as any appreciable rotation of the main or switch-operating shaft 2 occurs, this segment 62 will begin to obstruct the path which the keeper 64 would be compelled to follow, along with the rod 27, in a return movement to return the semaphore to "safe" position. The segment 62 extends around from its terminal part 63 to the other side of the fulcrum-head 7, where it merges with the side of the fulcrum-head, as seen in Fig. 1. Thus, the 70 segment 62 will obstruct the return movement of the semaphore-operating connection while the switch-operating mechanism is in any position around its 180° of travel, clear up to the extreme other position with 75 the lever 8 in the slot 12. It will not be possible to return the semaphore-operating mechanism to "safe" position until the switch-operating mechanism has been brought entirely back so that the switch is 80 85 safely closed.

It will be understood that when the switch-operating lever 8 returns in its horizontal position, the semaphore-operating lever 36 will be found also in horizontal 90 position, and the slot 42 in the lever 8 will receive the lug 41 of the lever 36; and then when the switch-operating lever 8 is brought down to vertical position, the semaphore-operating mechanism will be operated back, 95 bringing the semaphore back into "safe" 100 position as the switch-operating lever 8 is brought down into position for locking again. It will not be possible to lock this lever 8 until the opening 14 in the ear 13 105 has been brought far enough out of the fulcrum-head 7 to admit the shackle of the padlock. Not until this has occurred will the semaphore have been brought completely 110 into "clear" or "safe" position. It is thus seen that the operator is compelled to bring the semaphore into "safe" position before he can lock the switch; so that display of "danger" by the semaphore when the switch is safe may also be prevented, as well as 115 the more serious irregularity of displaying "safety" when the switch is open, which is prevented in the manner above described.

It will be noted that, until the lug 41 of the semaphore-operating lever 36 is entirely 120 withdrawn from the slot 42 in the switch-operating lever 8, it is impossible to operate the semaphore independently of the switch-operating lever 8, even though the segment 62 has not come within the path of the operative connection to the semaphore. Thus, 125 double protection is afforded at this period of the operation of the switch mechanism, amply guarding against false removal of the semaphore from "danger" position, 130

even though the segment 62 should fall somewhat short of promptly performing its duty in this period of the operation.

I have illustrated and described a switch stand requiring a rotation of the main shaft through 180°, but since the semaphore mechanism is completely operated before the operation of the switch mechanism is commenced, it is immaterial what degree of movement the switch stand mechanism requires in throwing the switch. Some switch stands require a rotation of the main shaft through only 90°, and others may involve more or less degree of rotation, but my improved semaphore operating and locking mechanism may be incorporated in such a switch stand with the parts properly proportioned, and will operate correctly according to the principle herein set forth in such a switch stand mechanism.

As shown in Fig. 1, the fulcrum-lug 43 is formed on top of the lower bracket 17, but, for convenience in providing for both right hand and left hand switch stands, such a fulcrum-lug may be formed on the side of the bracket. Thus, as shown in detail in Fig. 7, the bracket 17^a may have companion lugs 68 on opposite sides, and the link 44^a may extend across the top of the bracket and have a shank 69 extending down between the companion lugs 68 on the bracket, and the bolt 45 may pass transversely through the lugs and through the shank of the link. If the switch stand is to be of reverse construction, this link may be shifted to the other side with its shank 69 between the lugs 68 on that side of the bracket 17^a. With such provision, the only part requiring a different part to be substituted for it will be on the fulcrum-head 7 with its segment 62. This fulcrum-head, to operate on the other side, requires its segment placed diametrically opposite.

The above details are particularly referred to in order to make clear the illustration of my preferred construction. However, it will be understood that such details may be altered, and various other minor changes may be made, without departing from the scope or spirit of my invention as set forth in the following claims:

I claim—

1. In combination with a switch band and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together during the initial movement of said switch-operating lever, and operative connection between this semaphore-operating lever and the semaphore-arm, whereby said arm is completely operated during said initial swinging of the switch-operating lever.

lever pivoted concentric with the pivoting of the switch-operating lever, means for operative engagement between the switch-operating lever and this semaphore-operating lever, whereby the two levers swing together 70 during the initial movement of said switch-operating lever, and operative connection between this semaphore-operating lever and the semaphore-arm, whereby said arm is completely operated during said initial 75 swinging of the switch-operating lever.

2. In combination with a switch stand and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring to be initially swung on its pivot in the fulcrum-head to disengage from 80 the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together 85 during the initial movement of said switch-operating lever, and operative connection between the semaphore-operating lever and the semaphore-operating rod, whereby the arm is completely 90 operated during said initial swinging of the switch-operating lever.

3. In combination with a switch stand and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring

to be initially swung on its pivot in the fulcrum-head to disengage from the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together during the initial movement of said switch-operating lever, a semaphore-operating rod connected to said arm, and operative connection between the semaphore-operating lever and the semaphore-operating rod, whereby the arm is completely 100 operated during said initial swinging of the switch-operating lever.

3. In combination with a switch stand and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring

to be initially swung on its pivot in the fulcrum-head to disengage from the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together during the initial movement of said switch-operating lever, a semaphore-operating rod connected to said arm, and operative connection between the semaphore-operating lever and the semaphore-operating rod, whereby the arm is completely 110 operated during said initial swinging of the switch-operating lever.

3. In combination with a switch stand and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring

to be initially swung on its pivot in the fulcrum-head to disengage from the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together during the initial movement of said switch-operating lever, a semaphore-operating rod connected to said arm, and operative connection between the semaphore-operating lever and the semaphore-operating rod, whereby the arm is completely 115 operated during said initial swinging of the switch-operating lever.

3. In combination with a switch stand and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring

to be initially swung on its pivot in the fulcrum-head to disengage from the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together during the initial movement of said switch-operating lever, a semaphore-operating rod connected to said arm, and operative connection between the semaphore-operating lever and the semaphore-operating rod, whereby the arm is completely 120 operated during said initial swinging of the switch-operating lever.

3. In combination with a switch stand and a semaphore thereon, a main switch-operating shaft, a fulcrum-head fixed to said main shaft to rotate it, a switch-operating lever pivoted in the fulcrum-head, a stationary plate having a slot, said switch-operating lever being received in the slot and requiring

to be initially swung on its pivot in the fulcrum-head to disengage from the slot and permit rotation of the fulcrum-head and main shaft, a vertically movable semaphore-arm, means supporting the arm for vertical movement, a semaphore-operating lever pivoted concentric with the pivoting of the switch-operating lever, means for operative engagement between the switch-operating lever and this semaphore-operating lever, whereby the two levers swing together during the initial movement of said switch-operating lever, a semaphore-operating rod connected to said arm, and operative connection between the semaphore-operating lever and the semaphore-operating rod, whereby the arm is completely 125 operated during said initial swinging of the switch-operating lever.

130

4. In combination with a switch stand and a semaphore thereon, a main switch-operating shaft, a fulcrum-head fixed to said main shaft to rotate it, a switch-operating lever 5 pivoted in the fulcrum-head, a stationary plate having a slot, said switch-operating lever being received in the slot and requiring to be initially swung on its pivot in the fulcrum-head to disengage from the slot and 10 permit rotation of the fulcrum-head and main shaft, a vertically movable semaphore-arm, means supporting the arm for vertical movement, a semaphore-operating lever pivoted concentric with the pivoting of the 15 switch-operating lever, means for operative engagement between the switch-operating lever and this semaphore-operating lever whereby the two levers swing together during the initial movement of said switch-operating lever, operative connection between 20 said semaphore-operating lever and said arm, whereby the arm is completely operated during said initial swinging of said switch-operating lever, a segment on said fulcrum-head, and means comprised in said operative connection to engage with said segment and prevent operation of said arm independently of the operation of the switch-operating lever during removal of the switch-operating 25 30 lever from its initial position.
5. In combination with a switch stand and a semaphore thereon, a main switch-operating shaft, a fulcrum-head fixed to said main shaft to rotate it, a switch-operating lever 35 pivoted in the fulcrum-head, a stationary plate having a slot, said switch-operating lever being received in the slot and requiring to be initially swung on its pivot in the fulcrum-head to disengage from the slot and 40 permit rotation of the fulcrum-head and main shaft, a vertically movable semaphore-arm, means supporting the arm for vertical movement, a semaphore-operating lever pivoted concentric with the pivoting of the 45 switch-operating lever, means for operative engagement between the switch-operating lever and this semaphore-operating lever, whereby the two levers swing together during the initial movement of said switch-operating lever, a semaphore-operating rod 50 connected to said arm, operative connection between said semaphore-operating lever and said semaphore-operating rod whereby the arm is completely operated during said initial swinging of said switch-operating lever, a segment on said fulcrum-head, and a keeper on said semaphore-operating rod, adapted to engage with said segment and prevent operation of said arm independently 55 of the operation of the switch-throwing lever during removal of the switch-throwing lever from its initial position.
6. In combination with a switch stand and a semaphore thereon, a main switch-operating shaft, a fulcrum-head fixed to said 60 65
- main shaft to rotate it, a switch-operating lever pivoted in the fulcrum-head, a stationary plate having a slot, said switch-operating lever being received in the slot, and requiring to be initially swung on its pivot 70 in the fulcrum-head to disengage from the slot and permit rotation of the fulcrum-head and main shaft, an upper bracket and a lower bracket on said switch stand, a semaphore-column supported by said brackets, a semaphore-arm pivoted on the upper part of said column to swing in a substantially vertical plane, a semaphore-operating rod pivotally connected to said arm and passing down through said upper bracket, a 75 semaphore-operating lever pivoted concentric with the pivoting of the switch-operating lever, means for operative engagement between the switch-operating lever and this 80 semaphore-operating lever whereby the two levers swing together during the initial movement of the switch-operating lever, a link fulcrumed on said lower bracket, a primary connecting rod from said 85 semaphore-operating lever to said link, and a secondary connecting rod from said link to said 90 semaphore-operating rod, below said upper bracket, whereby said semaphore-arm is completely operated during said initial swinging of said switch-operating lever. 95
7. In combination with a switch stand and a semaphore thereon, a main switch-operating shaft, a fulcrum-head fixed to said main shaft to rotate it, a switch-operating lever pivoted in the fulcrum-head, a stationary 100 plate having a slot, said switch-operating lever being received in the slot, and requiring to be initially swung on its pivot in the fulcrum-head to disengage from the slot and permit rotation of the fulcrum-head 105 and main shaft, an upper bracket and a lower bracket on said switch stand, said brackets being adjacent to the main shaft, a semaphore-column supported by said 110 brackets, a semaphore-arm fulcrumed on the upper part of said column to swing in a substantially vertical plane, a semaphore-operating rod pivotally connected to said arm and extending down through said upper bracket, a semaphore-operating lever 115 pivoted concentric with the pivoting of the switch-operating lever, means for operative engagement between the switch-operating lever and this semaphore-operating lever whereby the two levers swing together during the initial movement of said switch-operating lever, a link fulcrumed on said lower bracket, a primary connecting rod from said 120 semaphore-operating lever to said link, a secondary connecting rod from said link to said semaphore-operating rod, below said upper bracket, a segment on said 125 fulcrum-head, withdrawn from said semaphore-operating rod while said switch-operating lever is in the slot in the plate, but 130

approaching said semaphore-operating rod when the fulcrum-head and main shaft are rotated, and a keeper fixed on said semaphore-operating rod above said upper bracket, adapted to rise with the semaphore-operating rod above the level of the upper surface of the segment, and to engage downward against the segment to prevent operation of said semaphore arm independently of the operation of the switch-throwing mechanism when said segment has approached said semaphore-operating rod.

8. In combination with a switch stand comprising a switch-operating element movable in one plane and a semaphore-element movable in another plane, obstructing means carried by the switch-operating element, and means on the semaphore-element to engage with the obstructing means, whereby the switch-operating element, by its position, controls the operation of the semaphore-operating element, said engaging means also constituting means for adjusting said semaphore-operating element.

25 9. In combination with a switch stand comprising a switch-operating element and a semaphore element, part of the switch-operating element being initially movable in a plane substantially parallel with the line of movement of the semaphore element, a bracket on the switch stand, a link, a fulcrum for the link on the bracket, a rod connected to the link, and disengageable means pivotally connecting said rod to said part 30 of the switch-operating element, and another rod connected to said link and to said semaphore element.

10. In combination with a switch stand comprising a switch-operating element and 40 a semaphore element, part of said switch-

operating element being initially movable in a plane substantially parallel to the line of movement of the semaphore element, a bracket on the switch stand, a link, operative connection from the link to said part 45 of the switch-operating element, and operative connection from the link to said semaphore element, extensions on opposite sides of the bracket below its top, an angularly extended shank on said link, and pivotal 50 connection between the shank and one of the extensions on the bracket, whereby the link is pivoted at the side of the bracket below the top of the bracket, but extends across the top of the bracket to receive said 55 operative connections, and whereby said link is reversible on the bracket for this shank to have pivotal connection with the extension on the other side of the bracket.

11. In combination with a switch stand 60 comprising a switch-operating element and a semaphore element, part of said switch-operating element initially moving in a plane substantially parallel to the line of movement of said semaphore element, an 65 auxiliary element movable with said part of the switch-operating element while it is initially moving, but disengageable from said part after the initial movement, a bracket on the switch stand, a link, operative connection from the link to said auxiliary element, operative connection from the link to said semaphore element, and an extension on the bracket to which said link is pivoted.

FRANK C. ANDERSON.
